UNITED STATES PATENT OFFICE.

HERMAN R. FREUND, OF BROOKLYN, NEW YORK, ASSIGNOR TO INTERTYPE CORPORATION, OF BROOKLYN, NEW YORK, A CORPORATION OF NEW YORK.

FONT DISTRIBUTOR FOR TYPOGRAPHICAL MACHINES.

Application filed May 25, 1923. Serial No. 641,472.

To all whom it may concern:

Be it known that I, HERMAN R. FREUND, a citizen of the United States, residing at Brooklyn, in the county of Kings and State 5 of New York, have invented new and useful Improvements in Font Distributors for Typographical Machines, of which the following is a specification.

The present invention relates to improvements in typographical machines and more especially to those of the class wherein matrices stored in a magazine or magazines are released under control of the keyboard, assembled in a line, and a cast taken therefrom, after which the matrices composing the line are returned by a distributor to the respective channels of the magazine from which they were drawn, a machine of this 15 same general class being illustrated and described in Letters Patent No. 436,532, granted September 16, 1890 to O. Mergenthaler.

The present invention relates more particularly to typographical machines of this 20 class which are constructed with two separate magazines, from either or both of which matrices belonging to different fonts or sets may be withdrawn and assembled into a line from which a cast may be taken, and the primary object of this invention is to provide novel and improved means whereby the matrices belonging to the different fonts or sets and which were withdrawn from either or both of the magazines 25 and assembled into the line may, after the cast has been taken therefrom, be returned to the appropriate channels of the respective magazines through the use of a single distributor similar to that shown and described in the patent above referred to, whereby the matrices are distinguished and separated according to character, and a font distributor which distinguishes the matrices according to font and separates and distributes them to the respective magazines to 30 which they belong.

To these and other ends, the invention consists in certain improvements and combinations and arrangements of parts, all as 35 will be hereinafter more fully described, the features of novelty being pointed out particularly in the claims at the end of the specification.

In the accompanying drawing:

Figure 1 represents a side elevation, partly in section, of a part of a typograph-

ical machine to which the preferred embodiment of the present invention is applied;

Figure 2 represents, on an enlarged scale, a vertical longitudinal section through the 60 font distributor shown in Figure 1;

Figure 3 represents, on a further enlarged scale, a section taken transversely through the font distributor;

Figures 4 and 5 are perspective views 65 showing, respectively, matrices belonging to different fonts or sets and constructed for use in carrying out the invention; and

Figure 6 represents a section taken longitudinally through the font distributor and 70 the adjacent portions of the channel entrance for the distributor and the upper magazine.

Similar parts are designated by the same reference characters in the several views. 75

The present invention is applicable generally to typographical machines of the kinds employing circulating matrices which are adapted to be drawn from and subsequently returned to different magazines according to font or set, the invention being particularly applicable to machines of the linotype class, substantially as represented in the patent herein referred to. The preferred embodiment of the invention is 80 shown in the accompanying drawing and will be hereinafter described in detail, but it is to be understood that the invention is not restricted to the precise construction shown, as equivalent constructions are contemplated and such will be included within the scope of the claims.

In the accompanying drawing, M and M' represent two magazines which are mounted in superposed relation within the machine, 85 which may be of the linotype class and provided with well known or any suitable means for releasing matrices from either or both magazines for assembling into a line, these magazines being preferably of the 90 usual construction having grooves M³ formed in their top and bottom plates to provide channels to guide and receive the different matrices according to the characters which they bear.

1 represents the permuted distributor bar and 2, 3 and 4 the distributor screws which feed the matrices along said bar, the distributor bar and cooperating screws being preferably similar in construction and mode 100 of operation to such parts as commonly used in machines of the linotype class and as

shown and described in the above-noted patent, it being understood that the distributor bar and cooperating screws function to distinguish and separate the matrices according to the characters which they bear and that the matrices drop from the bar 1 at different points in its length, according to the characters on such matrices. 5 represents a channel entrance which is arranged beneath the distributor bar and is provided with partitions 6 which provide channels or passages which are arranged to receive the corresponding matrices as they are released and drop from the distributor bar.

15 The distributing means provided by the present invention for distinguishing and separating the matrices according to the fonts or magazines to which they belong, is interposed between the channel entrance 5 and the upper or matrix-receiving ends of the magazines and it receives the matrices which have been separated according to the characters which they bear and distinguishes and separates such matrices according to the fonts or magazines to which they belong. Preferably and as shown in the present instance the font distinguishing means according to the present invention comprises a font distinguisher 7 which embodies a top plate 8 which is formed on its under side with grooves 9 which are alined with the grooves M^3 of the upper magazine and with the matrix passages formed between the partitions 6 of the channel entrance. The ribs or walls 10 which intervene or separate the channels 9 are formed with laterally-projecting ledges 11 which provide rails to support or sustain matrices belonging to the upper magazine M during the passage of such matrices through the font distributor and to permit other matrices belonging to the lower magazine M' to drop from the font distributor into a chute or hopper 12 which leads to the upper end or matrix entrance of the lower magazine M', this hopper containing partition plates 13 which provide matrix passages therein which are alined with the grooves 9 and with the matrix passages of the channel entrance 5 and the matrix guiding grooves M^3 of the lower magazine. These partition plates 13 preferably project for a suitable distance upwardly into the font distributor, substantially as shown.

55 Matrices suitable for use in conjunction with the matrix distributing means hereinbefore described may be constructed substantially as represented in Figures 4 and 5. The matrices in each instance may be similar in general construction and outline to those commonly used in machines of the Linotype class, they having lugs or ears at their corners for supporting and guiding them while being handled by the different mechanisms of the machine and having per-

muted teeth in their notched upper ends to cooperate with the distributor bar 1, whereby they may be distinguished and separated according to the letters which they bear. However, the lugs or ears on one of the edges of the matrices are shaped differently on the matrices belonging to the different fonts, so that they may be distinguished and separated accordingly. For example, Figure 4 shows a matrix m' which is representative of those belonging to the font or set contained in the lower magazine M', this matrix having the usual permuted teeth m^2 formed in a notch in its upper end and having lugs or ears m^3 and m^4 projecting in pairs from its opposite edges. The lugs or ears m^3 are utilized according to the present invention to distinguish these matrices according to font and to enable them to be separated from matrices belonging to another font or set. For this purpose, the lugs or ears m^3 of the matrix m' are in the present instance reduced in thickness throughout their areas so that they will enter the respective channels 9 of the font distributor, but will receive no support from the ledges 11. Figure 5 shows a matrix m representative of one of the matrices of the font which may be contained in the upper magazine M, this matrix m having permuted teeth m^2 for distribution by the distributor bar 1, according to character, and lugs or ears m^5 and m^6 projecting in pairs from its opposite edges. The lugs or ears m^6 of the matrix m are preferably identical with the lugs or ears m^4 of the matrix m' , but the lugs or ears m^5 of the matrix m are partially reduced in thickness to substantially the thickness of the lugs m^3 of the matrix m' , by grooves m^7 and m^8 which extend longitudinally of the matrix adjacent to the body thereof, leaving overhanging portions m^9 and m^{10} whose thickness is greater than that of the lugs m^3 of the matrix m' and these overhanging portions are of sufficient width to overlap and rest upon the ledges 11 of the respective grooves 9.

By constructing the matrices belonging to the different fonts with identical lugs or ears m^4 and m^5 , substantial advantages are obtained. In machines of this class as ordinarily constructed and used, the matrices are guided in the channels M^3 of the magazines and these channels bear a proportionate relation in width to the thickness of the lugs or ears of the matrices. The matrices while being distributed into the magazines are guided mainly by the lugs or ears which engage in the lower channels of the magazine in preference to the upper channels thereof, and by forming the lugs or ears m^4 and m^6 of the matrices of the same thickness and in proportionate relation to the width of the guiding channels in the magazines, the proper guiding of the matrices while

contained in or passing through the magazines is not disturbed, and, moreover, the usual escapement means for releasing and delivering the matrices from the magazines 5 are not affected by any change in the form or dimension of the matrix. The only change made in the form of the matrix to enable the matrices to be distinguished and separated according to fonts involves the 10 ears m^3 and m^5 of the matrices, the ears m^3 of the matrix m' being thin to agree with the thickness of the lugs or ears m^5 of the matrix m at the points where these lugs or ears m^5 are grooved.

15 The mode of operation of font distributing means constructed in accordance with the present invention as herein described and using matrices of the kind above referred to, is as follows: Matrices are drawn 20 from either or both of the magazines M and M' , by any suitable means, such as the keyboard controlled escapement mechanism commonly used in machines of the linotype class, and the matrices so released are assembled in a line preparatory to the casting 25 of a type bar against the same, by any suitable mechanisms such as those commonly used in machines of the linotype class. After the cast has been made the matrices 30 composing the line are distributed so that each matrix is returned to the appropriate channel of its respective magazine. The distribution is effected by first separating the matrices according to character, this being 35 preferably done in the usual way by engaging the matrices by their permuted teeth on the distributor bar 1 and propelling the matrices while so suspended by the continuously revolving screws 2, 3 and 4, the 40 matrices being thus caused to travel along the distributor bar 1 until the permutations on the different matrices reach the corresponding permutations on the bar 1, whereupon the matrices will be released from the 45 bar 1 at appropriate points in its length and they will drop by gravity into the channel entrance or hopper 5. This step in the distribution of the matrices is preferably identical with the usual method of distributing 50 matrices according to character in the usual type of machine of this class. The matrices which have been distinguished and separated according to character are then distinguished and separated according to 55 font and are then directed into their appropriate magazines. This is accomplished according to the present invention by the font distributor 7 which receives the matrices from the channel entrance 5, distinguishes and separates them according to font and directs them into the magazines M and M' respectively. All matrices bearing 60 the same character but belonging to both magazines will pass through the respective channel or passageway of the chan-

nel entrance 5 and will enter the channel of the font distributor aligned therewith. the uppermost lugs or ears m^3 or m^5 of these matrices, which, it is to be understood, are travelling downwardly in a direction 70 endwise of the matrix and by gravity, will enter the respective channel or groove 9 in the top plate 8 of the font distributor while the lower portions of the matrices will travel in the space formed between the adjacent partition plates 13. The matrices like the matrix m in Figure 5 and which belong in the upper magazine M will travel directly through the font distributor, by reason of the presence of the ribs or projections m^9 and m^{10} on its lugs or ears m^5 , these ribs or projections overlying and hence resting on the respective laterally directed ledge or rail 11 and thereby supporting 75 or sustaining these matrices within the font distributor. Such matrices will, therefore, pass directly through the font distributor and will enter their appropriate channels in the upper magazine M . However, matrices like the matrix m' in Figure 4 and which belong in the lower magazine M' , upon entering the font distributor 7 from the channel entrance 5 will receive no support from the laterally projecting ledges 80 or rails 11, owing to the reduction in the thickness of their lugs or ears m^3 and the absence of ribs or projections thereon, and hence such matrices, upon entering the font distributor, will drop by gravity in a vertical direction edgewise of the matrix into the passageway formed between the adjacent partition plates 13, these matrices being then guided by the chute or hopper 12 into their respective channels in the lower 85 magazine M' .

90 From the foregoing, it will be understood that the matrices m of one set or specie or belonging to the font contained in the magazine M will be supported or sustained, during their passage through the font distributor by reason of the presence, on their uppermost lugs, of supporting or sustaining means formed by the longitudinal grooves in such lugs, such supporting or 95 sustaining means engaging the ledges or rails on the top plate of the front distributor; whereas matrices of another set or species or belonging to another font such as that contained in the magazine M' have no supporting or sustaining means on their uppermost lugs, and hence the lugs of these matrices will not engage the ledges or rails of the font distributor so that such matrices will drop edgewise by gravity from the font 100 distributor into the chute or hopper 12 and will pass on into their respective channels of the magazine M' . This will be understood clearly from Figures 3 and 6, the latter figure particularly illustrating the 105 manner in which matrices like the matrix 110

115

120

125

130

m, Figure 5, are supported by the ledges or rails in the font distinguisher and therefore pass into the magazine *M* aligned therewith, while matrices like the matrix *m'*, 5 Figure 4, do not engage or receive support from the ledges or rails in the font distributor and therefore such matrices drop into the chute or hopper 12 and pass into the magazine *M'*. It will be obvious that the 10 means substantially as herein shown for separating two sets, fonts or species of matrices may be applied to machines having four magazines or any desired number of magazines which is a multiple of two magazines, and that the magazines and the font distributor may be relatively shiftable so that the font distributor may cooperate with any desired pair of magazines.

It will be noted that no change has been 20 made in the outline of the matrix as compared with those of the kind commonly used in machines of the linotype class, and that the only change made consists in reducing the thickness of a pair of the lugs or 25 ears on one set or species of matrices to equal substantially the thickness of the grooved portion of the corresponding lugs or ears of the matrices of the other set or species. Inasmuch as the matrices are 30 guided and manipulated largely by the lower lugs *m⁴* and *m⁶* and that no change in these lugs is necessary, no changes in the usual mechanisms of standard machines of this type is necessary to enable them to handle 35 matrices of the construction herein described. The reduction in the thickness of the lugs *m³* may permit some wavering of such lugs in the upper channel of the standard magazine, although this has not been 40 found objectionable in carrying the invention into practice. By extending the partition plates 13 upwardly so as to project above the lower edges of the matrices passing through the font distributor on their 45 way to the upper magazine, as shown, the matrices are at all times under control while passing through the font distributor for guidance into the appropriate channels of the magazines.

50 If desired, the chute or hopper 12 may be hinged at 14 to the upper end of one of the magazines so that it may be swung downwardly and thus render accessible the upper end of the lower magazine or the interior 55 of the chute, and also the top plate 8 of the font distributor may be hinged at 15 to permit the same to be swung upwardly, thus rendering accessible the upper end of the upper magazine and the interior of the font distributor.

I claim as my invention:—

1. In a typographical machine, a distributor for separating, according to font, matrices having aligned grooves extending 65 longitudinally across the upper and lower

lugs at one edge thereof, comprising a rail to engage the grooved lugs and thereby suspend therefrom matrices of one font while travelling in a vertically edgewise position and to permit passage without engagement therewith of matrices having ungrooved lugs and belonging to another font. 70

2. In a typographical machine, a distributor for separating matrices of one font having aligned grooves extending longitudinally through the upper and lower lugs at one edge thereof and matrices of another font having upper and lower lugs of reduced thickness, comprising a rail to engage the grooved upper and lower lugs 75 of the matrices belonging to one font and thus suspend such matrices in vertically edgewise position and to permit passage without engagement thereof of the reduced thickness lugs of matrices belonging to another font. 80

3. In a typographical machine, a distributor for separating, according to font, matrices having aligned grooves extending longitudinally of the upper and lower lugs 90 at one edge thereof, comprising a channel for the vertically edgewise passage of matrices belonging to different fonts, and a rail extending longitudinally of said channel and operative to engage the grooved 95 lugs and thereby suspend therefrom matrices belonging to one font and to permit passage without engagement therewith of matrices belonging to another font. 100

4. In a typographical machine, a distributor for separating matrices according to font comprising a channel for the passage of matrices belonging to different fonts while in vertically edgewise position, and a rail arranged in the upper portion of 105 said channel to engage in longitudinal grooves in the upper and lower lugs on one longitudinal edge of matrices belonging to one font while passing through said passage and to avoid engagement with the 110 ungrooved lugs on matrices belonging to another font. 110

5. In a typographical machine, a font distinguisher for separating, according to fonts, matrices having aligned grooves extending longitudinally across the upper and lower lugs at a longitudinal edge of such matrices from other matrices without such grooved lugs, comprising a passage for 115 matrices belonging to the different fonts and an opening in the bottom thereof and a rail extending longitudinally in said passage operative to receive the grooved lugs and thereby support matrices belonging to one font and thus conduct such matrices across 120 said opening and to avoid engagement with matrices having ungrooved lugs belonging to another font and thus permit such matrices to pass into said opening. 125

6. In a typographical machine, a font dis- 130

tinguisher comprising a passageway for the edgewise movement of matrices, those of one font having longitudinal grooves extending across the faces of the upper and lower lugs at one edge thereof, and those of another font having ungrooved lugs, and having a matrix discharge opening in the bottom, and a rail in the upper portion of said passageway and extending longitudinally thereof, said rail being operative to receive the grooved lugs and thereby suspend therefrom matrices belonging to one font and thus convey such matrices across said discharge opening and to avoid engagement with the ungrooved lugs of matrices belonging to another font and thus cause discharge of such matrices into said opening.

7. In a typographical machine, a font distributor having a passageway for the edgewise movement of matrices, those of one font having grooves extending longitudinally across the upper and lower lugs at one edge thereof, and those of another font having the upper and lower lugs at one edge thereof reduced in thickness, and a matrix discharge opening in the bottom of such passageway, and a rail extending longitudinally of and projecting laterally in the upper portion of said passageway, said rail being operative to engage the upper and lower grooved lugs of and suspend therefrom matrices belonging to one font and thereby conduct such matrices across said opening and to avoid engagement with the reduced-thickness lugs of matrices belonging to another font and thereby cause discharge of such matrices into said opening.

8. In a typographical machine having a plurality of magazines to contain respectively matrices belonging to different fonts and means for distributing the matrices according to the characters which they bear, the matrices belonging to one font having grooves extending longitudinally across the upper and lower lugs at one longitudinal edge thereof a font distinguisher having passageways to receive respectively the matrices distributed according to character and having openings for the discharge of the matrices therefrom into one or another magazine according to font, and means within the font distinguisher to engage the grooved upper and lower lugs and thereby support matrices belonging to one font and thus conduct such matrices for discharge into one magazine and to avoid engagement with other matrices without such grooved lugs and belonging to another font and thereby cause such matrices to discharge into another magazine.

9. In a typographical machine, means for distributing, according to font, matrices some of which have grooves extending longitudinally across the upper and lower lugs

at a longitudinal edge thereof and others of which have lugs of reduced thickness, to one or another magazine, comprising a passageway for the edgewise movement of matrices belonging to the different magazines, the passageway having an opening in the end for the discharge of matrices into one magazine and an opening in its bottom for the discharge of matrices into another magazine, a rail in the upper portion of said passageway operative to engage the grooved lugs and thereby suspend therefrom matrices belonging to one magazine and to conduct such matrices across the opening in the bottom of the passageway and to permit passage of other matrices with reduced-thickness lugs belonging to another font to said latter opening without engagement with said rail.

10. In a typographical machine, means for distributing matrices according to font to one or another magazine comprising a passageway for the edgewise movement of matrices belonging to different fonts and having an opening in its end for the discharge of matrices to one magazine and an opening in its bottom for the discharge of matrices into another magazine, a rail in the upper portion of said passageway operative to engage and thereby suspend matrices belonging to one font for movement past the bottom opening and to the end opening and to cause discharge of matrices belonging to another font to discharge into the bottom opening without engaging said rail, and laterally-spaced partition plates projecting upwardly through said bottom opening above the path of the lower edges of matrices suspended from said rail.

11. In a typographical machine adapted to store two sets of matrices those of one set having a groove longitudinal with the corner lugs or ears thereof, means to engage matrices belonging to the set having the groove and to conduct such matrices to their appropriate place of storage, the rail allowing the matrices of the other set to pass, without engagement therewith, to a different place of storage.

12. In a typographical machine adapted to use matrices having the lugs or ears at one side thereof provided with aligned grooves extending longitudinally thereof, a matrix passageway having a matrix discharge opening for the discharge of matrices transversely therefrom, and a rail operative to engage and direct matrices provided with said grooves past said opening and to cause matrices without such grooves to discharge transversely from the passageway into said opening without engaging the rail.

13. In a typographical machine, a matrix font distinguisher for separating matrices of one font having the lugs or ears at one

side thereof provided with alined grooves from those of another font without such grooves in their lugs or ears, comprising a passageway for the edgewise movement of 5 matrices, the passageway having an opening for the discharge of matrices transversely of the passageway, and a rail to cooperate with the lugs or ears of the grooves matrices to direct them past said opening and 10 allowing matrices without such grooves to discharge into said opening without engaging the rail.

14. In a typographical machine, a font 15 distinguisher for separating matrices of one font having the lugs or ears at one longitudinal side thereof provided with alined longitudinal grooves from those of another

font without such grooves in their lugs or ears, comprising a passageway for the end- 20 wise vertically edgewise movement of matrices, said passageway having a matrix discharge opening in its bottom, and a rail in the upper portion of said passageway and extending longitudinally thereof past said opening, said rail being operative to engage 25 the grooved lugs or ears of the matrices belonging to one font and thereby support and direct such matrices past said opening but allowing matrices without such grooved lugs or ears to enter said opening without en- 30 gaging the rail.

In testimony whereof I have hereunto set my hand.

HERMAN R. FREUND,
